UNITED STATES PATENT OFFICE.

OTTO SCHMID, OF REUTLINGEN, WURTTEMBERG, GERMANY.

APPARATUS FOR MANUFACTURING BARBED WIRE

Application filed December 6, 1923, Serial No. 679,016, and in Germany July 8, 1923.

The present invention relates to apparatus for manufacturing barbed wire particularly single wire barbed strand, in which two (or more) wires are twisted together at intervals and one (or more) of the wires cut through between the twisted portions and bent, while the remaining wire is left intact throughout. The bent ends of the cut wire thus form the barbs. Single wire barbed wire is that kind in which a single wire runs throughout and on which the members are mounted.

The machine according to the present invention operates in such a manner that the wires are first conveyed while lying closely adjacent to one another through a special guide to a twisting tool which is set in rotation intermittently and twists together the wires passing through. In order to obtain only local twisting the wires are secured either at one side or both in front of and behind the twisting tool. In the first case the twisted portions are twisted one after the other, either all in the same direction or alternatively left and right wounded, in the latter case two twisted portions are produced in the same time and are left and right twisted. Now, cutting tools come into action on one of the wires, and are so constructed that after the cutting of the wire they also effect the bending in such a way that one severed end stands upwards and the other severed end downwards, the ends lying in the same plane. When this operation is finished the wires are moved forward mechanically to an extent depending on the spacing required between the barbs, by means of a feed device, which may take the

40 form of a drawing-in roller for example. One embodiment of the invention is illustrated in the accompanying drawings in which

Fig. 1 is a side elevation of apparatus embracing the principles of the invention;

45 Fig. 2 is a front elevation of the apparatus;

Figs. 3 and 4 are elevational views showing respectively, the advance and return positions of the cutting and bending means;

50 Figs. 5 and 6 are plan and side elevational views of the cutting and bending tools, the wires being shown in section in Fig. 7;

Fig. 7 is an elevation of a modified form of cutting and bending means;

55 Figs. 8 and 9 are considerably enlarged

cross-sections of the wire-guide rolls showing two different forms of construction:

Figs. 10 and 11, and Figs. 12 and 13, illustrate, in end elevation, two different means for positioning alternate pairs of barbs at right angles to each other; and

Fig. 14 shows in end elevation another form of barbed bending device.

The wires *a* to be worked, which may have the same or different thickness, are introduced into the machine by a pair of drawing-in rollers *b* shown in Fig. 1 and also in section in two forms in Figs. 8 and 9, said rollers 7 being intermittently rotated from the cam disk 8 by means such as the pending oscillating lever 9 and the gear segment 10 at the free end. The gear 11 engaging in segment 10 (not shown) has a concealed unilateral acting drive pawl which causes the rollers to rotate only in the advanced direction, notwithstanding the swinging movement of the segment, and fed forward to a distance equal to that between barbs. The wires pass through a guide *c* and then approach a twisting tool *d*, of conventional form and serving to grip the wires to hold them from relative movement and to twist the wires on each side of the twisting tool. Adjacent to *d* is a gripping device *e* of any desired form, for securing the wires in a stationary condition during the twisting (see Fig. 1). Such a device may be arranged at each side of the twisting tool or only at one side, according to requirements, that is to say, if two twisted portions are desired at the same time (with left and right winding) or only one at a time is desired. The twisting-tool *d* may work in the latter case in such a manner, that it twists either always in the same direction, or alternately to left and to right. After the twisting operation the wires are taken up by a pair of drawing-in rollers *b* and the twisted wires are wound on a reel *f*.

After the twisting operation, the wires are fed forwards an amount equal to the distance between barbs when the twisted portions reach cutting tools *f* which cut through one of the wires between the twisted portions and in the forward and backward movement of the cutters bend the opposite ends *g* in the same plane and in two opposite directions, so that the barbs are formed as in Fig. 4, whereupon the wires *a* are moved another barbs-space distance.

While in known apparatus each of the wires has been fed independently by a special feed device, according to the present in- 110

vention they are moved forward by a single pair of rollers *b*, so constructed that the two wires *a* are pressed against one another together (see Figs. 8 and 9). Thereby the advantage is gained that an absolutely uniform feed movement is obtained for both strands, even when the thickness of the wire is not the same and irregularities appear.

This pressing together of the two wires *a* 10 is effected by their lying in the same recess *h* in the rollers *b* and this being furnished with oblique sides which exercise a wedging effect, that is to say press the two wires *a* one against the other. The recess *h* may be 15 in both rollers *b* as shown in Fig. 8 or in one only as shown in Fig. 9.

The wire guide *c* may be of any kind, but is so constructed that it prevents any turning of the wires *a* when the twisting tool *d* is 20 operating and thereby itself forms a firm holding device, so that in consequence of the provision of the second securing device *e* the wires are only twisted between these two devices. This second device *e* may be in the 25 nature of a slide, which has a slot whose width corresponds with the thickness of the wire.

The constructional form of the twisting tool *d* is likewise optional, as is also the 30 means of driving it. It consists essentially of some kind of rotary body, which merely seizes the wires in such a manner that they must participate in the rotation. The tools *d* operate according to the desired barbed 35 wire, either in one direction only or alternately in opposite directions.

The twisting tool *d* is rotated in manner not shown and retained by means of a slide 40 12, which is driven or controlled by the eccentric 13. The twisting point lies here in the tool *d* and the wires *a* are rigidly held at both sides thereof. For this purpose use is made of a lever 14, on the entering side, which is controlled by an eccentric groove 15, 45 and on the other side the retaining member *e* which is controlled by eccentric 16. The wire which is twisted at certain points, that is, at certain distances apart, now passes to the tools *f* which co-operate with the corresponding tools *m* and are mounted on a slide 50 17 controlled or driven by eccentric 18.

The tools *f* and *m* are so formed that in the forward movement they cut the one wire and bend one of the resulting ends, and on 55 the return movement, on the contrary bend the other end and to the other side (see Fig. 4), the two barbs so formed, however, lying in the same plane. This is assured by there being on the cutting tool *f*, on the one side a shoulder *i*, which in the forward movement passes beyond one of the wire ends *g*, but on the return movement comes into contact with and bends said end, as shown in Fig. 4. The 60 cooperating tool *m*, as shown in Fig. 5, has 65 an inclined cutting edge.

The formation and number of the different tools is of secondary importance as regards the essence of the invention, as is also the number of the wires to be worked simultaneously.

Figs. 6 and 7 illustrate the manner of the working of the tools. The lower tool *m* stands at an angle of 90° to the other tool *f*. In the meantime with the moving upward of the tool *f* the tool *m* moves forward. The shoulder *i* on tool *f* slides over the wire, then the cutting edge *h'* of the tool *f* (see Fig. 7) approaches the wire, cuts it through, and bends it in one direction. The tool *f* then returns, and in returning the shoulder *i* bends the other end of the cut wire in the opposite direction.

The form and number of the tools is of a secondary nature, as well as the number of the wires.

The barbs now lie all in one plane. With the swaged-like tools, illustrated in Figs. 10 and 11 as well as in 12 and 13, continuously one of the barb-pairs is bent above and the other below, so that they stand round the 80 guiding-wire. For this purpose the conical stamps *f'*, *f''*, press the wire into the respective recesses in dies *m'*, *m''*, by which the barbs *g* are bent from the positions of Figs. 10 and 12 into those of Figs. 11 and 13. By 85 the tools of the Figs. 10 and 11 the barbs *g* are bent upwards, and by the tools of the Figs. 12 and 13 the barbs of the next pair are bent downwards.

The swages may have any form, so, for instance they may have a form working only at one side as in Fig. 14. Here a stamp *f'''* works only against one of the barbs *g* and presses it downwards, whereby the other twin barb *g* of the same wire piece by means 105 of *m'''* is moved upwards. If the barbs of every other barb-pair are thus bent, the barbs stand around the guiding wire as shown in Fig. 14.

I claim:

1. Apparatus for manufacturing single strand barbed wire, comprising means for holding the wires against rotation, means for feeding the wires through the guide to a working point, said means being constructed to press the wires against one another, thereby to secure uniform speed of feed regardless of differences in thickness of the wires, securing means adjacent the working point on the opposite side from said holding means to prevent the wires from turning, a twisting device at the working point for twisting both wires simultaneously to form spaced twisted parts with parallel wire portions therebetween, cutting tools positioned beyond the twisting device and arranged to seize but one of the wires between adjacent twisted portions, cooperating edges on the tools for cutting through the seized wire, and shoulders on the tools 110 115 120 125 130

for bending the cut ends to form outstanding barbs.

2. Apparatus for manufacturing single strand barbed wire, comprising a guide for said wires, means for feeding the wires through the guide to a working point, said means being constructed to press the wires against one another, thereby to secure uniform speed of feed regardless of differences in the thickness of the wire, securing means adjacent the working point on the opposite side from said guide to prevent the wires from turning, a twisting device at the working point for twisting both wires simultaneously to form spaced twisted parts with parallel wire portions therebetween, cutting tools positioned beyond the twisting device arranged to sever but one of the wires between adjacent twisted portions, said cutting means being constructed to bend the cut ends of said wire to form outstanding barbs.
3. Apparatus according to claim 2, in which the feeding means comprises contact rollers constructed to form between them a wedge-shaped recess to press the wires against each other.
4. Apparatus according to claim 2, said wire guide being formed to prevent turning of the wires therein.

5. Apparatus according to claim 2, said twisting device being arranged to operate constantly in a single direction or alternately in opposite directions.

6. Apparatus according to claim 2, one of said cutting tools having a recess on one side, and means to move such tool in one direction to pass it over the wire to be cut, and means to give it a return movement in the opposite direction so as to seize and bend such cut wire.

7. Apparatus according to claim 2, said cutting tools being formed so that they bend one cut wire end on the forward movement, and the other cut wire end on the return movement.

8. Apparatus according to claim 2, said cutting tools being formed so that they bend one cut wire end on the forward movement, and the other cut wire end on the return movement, said other cut end being bent only after one of the cutting tools has descended.

9. Apparatus according to claim 2, a die means for turning every second pair of barbs to stand at an angle of 90° to the adjacent pairs of barbs.

In testimony whereof I affix my signature.

OTTO SCHMID.
